UNITED STATES PATENT OFFICE

ASHTON B. COLLINS, OF BIRMINGHAM, ALABAMA

DESIGN FOR A DOLL

Application filed September 24, 1932. Serial No. 45,053. Term of patent 14 years.

To all whom it may concern:

Be it known that I, ASHTON B. COLLINS, a citizen of the United States, residing at Birmingham, in the county of Jefferson, and State of Alabama, have invented a new, original, and ornamental Design for a Doll, of which the following is a specification, reference being had to the accompanying drawing, forming part thereof.

I claim:

The ornamental design for a doll, as shown.

ASHTON B. COLLINS.
